UNITED STATES PATENT OFFICE.

FRANKLIN SCHNEIDER, OF CLEVELAND, OHIO, ASSIGNOR, BY MESNE ASSIGNMENTS, TO THE VAN DORN ELECTRIC TOOL COMPANY, OF CLEVELAND, OHIO, A CORPORATION OF OHIO.

ELECTRICAL SWITCH.

1,104,737.

Specification of Letters Patent. Patented July 21, 1914.

Application filed February 20, 1913. Serial No. 749,645.

To all whom it may concern:

Be it known that I, FRANKLIN SCHNEIDER, a citizen of the United States, and a resident of Cleveland, county of Cuyahoga, and State of Ohio, have invented a new and useful Improvement in Electrical Switches, of which the following is a specification, the principle of the invention being herein explained and the best mode in which I have 10 contemplated applying that principle, so as to distinguish it from other inventions.

The subject of the present invention is an electrical switch adapted primarily for use in connection with an electrically operated 15 tool, such as a drill or the like. The features to be desired in a switch intended for the above purposes are simplicity of construction, convenience of disposition relative to the operator, together with rapidity 20 of operation. The present invention fulfills the above requirements and possesses also the advantage of comparative low cost.

To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of the various mechanical forms in which the principle of the invention may be used.

In said annexed drawing:—Figure 1 is a 35 central vertical section through the casing taken on the line 1—1, Fig. 2, but showing the operating mechanism in side elevation; and Fig. 2 is a section on the line 2—2, Fig. 1, but showing the switch mechanism in side 40 elevation for the purpose of clearness.

The general construction of my invention will be readily seen from Fig. 1. I provide a suitable split casing consisting of a base 1 and a cover or handle portion 2 which may 45 be fastened together by any suitable means. It is of no importance in the present connection as to how the switch casing will be attached to the casing of the tool, but it may be stated that the part 2 of the casing will 50 preferably form one of the handles by which the tool is held. In the base of the casing there is journaled a pin 4 upon which is oscillatorily mounted a switch member 5 adapted to bridge, in Fig. 1, a 55 plurality of spaced spring contacts 6 suit-

ably attached to a block 7 of insulating material. Suitable contact strips 8 are attached to the switch member and may be of any desired material. The switch member 5 is also of insulating material of some type. 60

The circuit is closed when the switch member 5 is in the position shown in Fig. 1. Wires 9 are attached to the contacts 6 and will lead to the operating means for the electrical tool which is not shown. The 65 means for rapidly operating the switch member comprise a second oscillatory member 10 mounted upon a suitable axis, consisting of a pin 11 attached to the handle of the casing. The second oscillatory member 10 70 is mounted to swing in the same plane as the switch member and is hollowed out at its forward end forming a recess adapted to receive a plunger 12 which is spring-pressed by means of a coil spring 13 mounted in the 75 recess in the member. At its forward end this oscillatory member is provided with two cup-shaped recesses 14 in which there may engage two plungers 15 and 16 mounted in alignment with each other in opposite 80 sides of the casing, and at such a point on the handle that they may be readily operated by the hand of the operator.

The operation of the switch will be readily understood from the foregoing description. To close the circuit, the upper plunger 16 is pressed downward by the operator, thus moving the operating plunger in the oscillatory member across the plate on top of the switch member. So long as the plunger 90 is on the upper side of the line through the axes of the switch member and the second member 10, its pressure will have no effect toward operating the switch member but as the plunger passes the center the 95 spring in the recess in the oscillatory member, which has been compressed during the first part of the movement of the member, will operate to throw the switch into its closed position with an extremely rapid 100 movement.

The pin upon which the switch member is oscillatorily mounted is held loosely in lugs 18 attached to the base of the casing, the upper portion 2 of the casing slipping down 105 over either end of the pin and retaining the same from disengagement with the lugs. By this construction it is possible to take down the switch readily to be examined or cleaned, or to have parts replaced, such as 110

the contact strip which must necessarily be removed at intervals. The simplicity of the switch is evident as it contains few parts of which but five move, which makes the device 5 compare very favorably with the usual type of rapidly operating or "snap off" switches which are complicated in construction. Rapidity of movement is in no way sacrificed to simplicity, however, as the action 10 will take place at a given point in the swing of the second oscillatory member and the speed of the switch member will be determined by the strength of the spring 13 which may be of considerable stiffness without 15 making the device difficult to operate.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In an electrical switch, the combination of a casing; an oscillatory switch member

therin: an extension attached to said casing and serving as a handle; an oscillatory member pivotally mounted at the outer end of said extension; a spring pressed plunger reciprocably mounted in said second member, said plunger being adapted upon oscillation of the latter to operate said switch member; and two buttons slidably mounted in opposite sides of said extension and adapted to actuate said oscillatory member.

2. In an electrical switch, the combination of an open casing; a plurality of aligned lugs therein; a switch member; a pin connecting said member and said lugs, said pin being loosely received in the latter; and a cover for said casing, adapted when in position to maintain said pin in position and upon removal to permit said pin to be slidably withdrawn from said lugs.

Signed by me, this 18th day of February, 1913.

FRANKLIN SCHNEIDER.
